STEAM TURBINE

Clarence E. Kenney and Charles D. Wilson, West Allis, Wis., assignors to Allis-Chalmers Manufacturing Company, Milwaukee, Wis., a corporation of Delaware

Application December 31, 1948, Serial No. 68,494

10 Claims. (Cl. 308—166)

1

The present invention relates to elastic fluid turbines and has for a principal object the provision of new and improved apparatus of this type.

A more specific object of the invention is to provide new and improved means for adjusting the rotating element of a turbine relative to the stationary element of the turbine in order to compensate for unequal relative longitudinal expansion and contraction of these elements.

This invention contemplates the use of an adjustable mechanism to connect the thrust bearing supporting means with the turbine casing in such a manner as to provide for more accurate adjustment than has been heretofore obtained.

Another object of the invention is to reduce the effect of lost motion in the turbine adjusting mechanism to such an extent that the displacement of the rotor relative to the casing resulting from lost motion in the adjusting mechanism is negligible.

Another object is to provide a structure that will cooperate with the turbine casing and thrust bearing but will not transmit stresses to the thrust bearing which are caused by transverse expansion and contraction of the parts of the turbine casing.

Still another object of the invention is to provide an adjusting means to compensate for relative longitudinal movement of a turbine casing and rotor, due to expansion and contraction, which is simple to operate. With this invention, the relative position of the rotor may be adjusted by one operator who has only to actuate a single element which may be a hand wheel.

Other objects will appear hereinafter as the description of the invention proceeds.

The novel features of the invention and how the objects are attained will appear more fully from this specification and the accompanying drawing showing one embodiment of the invention and forming a part of this application, and all of these novel features are intended to be pointed out in the claims.

In the drawing:

Fig. 1 is a fragmentary plan view of a turbine embodying this invention;

Fig. 2 is a section taken on line II—II of Fig. 1 looking in the direction of the arrows; and

Fig. 3 is a section taken on line III—III of Fig. 2 looking in the direction of the arrows.

The turbine herein illustrated as embodying this invention comprises a turbine casing 1 enclosing a turbine rotor 2. The rotor 2 has a shaft 3 which is journaled in bearings 4 (one of the bearings being indicated) and is provided with

2

a thrust bearing 5 carried by supporting means, herein shown as a yoke 6, connected to the turbine casing 1 by an adjustable connecting mechanism, and slidably mounted on a pedestal 8. The adjustable connecting mechanism may comprise two linkages 7A and 7B as here shown. The pedestal 8 is supported separately from the turbine casing 1.

The rotor 2 of the turbine carries rows of blading 9 and dummy blading for the labyrinth seal 10 which must be rotated in planes which bear a definite relationship to the stationary rows of blading 11 of the turbine casing 1. Temperature changes will produce unequal relative longitudinal expansion and contraction between the casing 1 and rotor 2 which will destroy this relationship and may result in clearances between the fixed and moving blades which are too large for efficient operation or it may cause serious damage by permitting the fixed and moving blades to come in contact with each other. Therefore, provision must be made to compensate for this unequal relative longitudinal expansion and contraction while permitting free simultaneous longitudinal expansion and contraction.

Simultaneous longitudinal expansion and contraction of casing 1 and rotor 2 is permitted by virtue of the slidable mounting of the yoke 6 on the pedestal 8, the yoke 6 cooperating with the turbine casing 1 through the linkages 7A and 7B and with the rotor 2 through the thrust bearing 5. The pedestal 8 is provided with a longitudinal recess 13 with which a lug 14, formed on the bottom of the yoke 6, coacts to maintain the center of the yoke 6 within a vertical plane passing through the rotational axis of the rotor 2. The yoke 6 is supported by the pedestal 8 on bearing surfaces 12. The yoke 6 is enclosed in a cover 15 secured to the pedestal 8 and provided with laterally extending lugs 16 which coact with laterally extending lugs 17 formed on the yoke 6. Lugs 16 and 17 are so disposed as to restrain the yoke 6 from rotation about the axis of rotation of the rotor shaft 3 but do not oppose longitudinal movement of the yoke 6 relative to the pedestal 8.

Compensation for unequal relative longitudinal expansion and contraction of the casing 1 and rotor 2 is accomplished by adjusting the effective length of the linkages 7A and 7B thus varying the relative position of the yoke 6 and the casing 1.

Since the relatively stationary part 18 of the thrust bearing 5 is rigidly mounted in the yoke 6 and cooperates with the relatively movable thrust bearing part 19 which is rigidly mounted

on the shaft 3 of the rotor 2, a change in the relative positions of the yoke 6 and the casing 1 will effect a corresponding change in the relative positions of the casing 1 and the rotor 2. The adjustable linkages 7A and 7B are here shown disposed on diametrically opposite sides of the rotor shaft and are identical except for eccentrics 20 which are opposite hand, as will more fully appear.

The connecting mechanism comprises members connected to the casing 1 and engaging the eccentrics 20 rotatably mounted on the yoke 6. The connecting mechanism is shown here as comprising links 21 pivotally connected by pins 22 to laterally extending lugs 23 formed on the turbine casing 1 and engaging the eccentrics 20 rigidly mounted on rotatable shafts 24 journaled in the yoke 6. The eccentrics 20 are restrained from rotation relative to the shafts 24 by keys 25. The shafts 24 are adapted to be rotated simultaneously by levers 26 which are mounted on the shafts 24 and restrained from rotation relative to the shafts 24 by keys 27. The levers 26 are movable in a plane perpendicular to the longitudinal axis of the shafts 24 by a lever actuating mechanism 28 which slidably engages slots 29 in the end portions of the levers 26. Movement of the levers 26 will cause the shafts 24 and the eccentrics 20 to rotate and the rotation of the eccentrics 20 in the links 21 will move the yoke 6 longitudinally relative to the turbine casing 1 thereby adjusting the relative positions of the turbine casing 1 and rotor 2.

It is desirable to limit the extent to which the relative positions of the turbine casing and rotor may be varied. To accomplish this, the links 21 are provided with radially extending flanges 30 disposed on opposite sides of the yoke 6 and adapted to abut limit plates 31, mounted on the yoke 6, when the maximum and minimum displacement of the rotor 2 is achieved. It is apparent that the thickness of the limit plates 31 will determine the range of longitudinal adjustment.

The embodiment of the lever actuating mechanism 28 herein shown and described is illustrative only and other means for actuating the lever 26 will be apparent to those skilled in the art. As here shown, the ends of the lever 26 are slotted at 29 to receive trunnions 33 extending from opposite sides of a rectangular block 34. The block 34 has a threaded opening 35 extending through it parallel to the rotor shaft 3. Through this opening 35 is disposed a threaded rod 36 the threads of which cooperate with the threads of the threaded opening 35 and the end portions of which 37 and 38 are reduced in diameter. One end 37 is journaled in a bearing 39 supported by the yoke 6. The other reduced end portion 38 of the rod 36 is provided with the worm wheel 40 and is journaled in a bracket 41 which is rigidly mounted on the yoke 6. Spacers 42 are mounted on the reduced end portion 38 of the rod 36 and bear against opposite sides of the bracket 41 thereby preventing longitudinal displacement of the rod 36 relative to the yoke 6. On one end of a shaft 43 is secured a worm 44 which engages the worm wheel 40. The other end of the shaft 43 carries a handwheel 45 for turning the shaft 43. It is apparent that the turning of the handwheel 45 will cause the threaded rod 36 to rotate and the block 34 to run along the rod 36 thus displacing the levers 26 and adjusting the relative positions of the turbine casing 1 and rotor 2 as hereinbefore described.

The proportions of the worm 44, worm wheel 40, rod 36, levers 26 and eccentrics 20 should be such that there is a known relation between the angular displacement of the handwheel 45 and the relative movement of the turbine casing 1 and rotor 2. For example, the proportion might be such that the rotation of the handwheel 45 through 360° would cause a relative longitudinal movement of the rotor 2 of 0.001".

It will now be obvious that, with this invention, small relative movements between the turbine casing 1 and rotor 2 may be produced by relatively large displacements of the actuating means (shown here as handwheel 45) thus simplifying accurate adjustment. It will also be obvious that changes in the relative positions of the turbine casing 1 and rotor 2 resulting from lost motion in the lever actuating mechanism 28 will be so small as to be negligible since the amplitude of such lost motion is greatly reduced through the action of the levers 26 and eccentrics 20.

The pivotal connection of the links 21 to the casing 1 by the pins 22 is such that lateral expansion and contraction of the casing will be unhampered and strains and accompanying stresses of such expansion and contraction cannot be transmitted to the yoke 6 and thrust bearing 5.

From the foregoing, it will be apparent to those skilled in the art that the illustrated embodiment of the invention accomplishes the objects of the invention. It will also be obvious to those skilled in the art that the invention is not limited to the form shown but is susceptible of various other changes and modifications without departing from the spirit of the invention and that, accordingly, the disclosure herein is illustrative only and the invention is not limited thereto.

It is claimed and desired to secure by Letters Patent:

1. In an elastic fluid turbine, the combination comprising: a casing; a rotor within said casing; a thrust bearing for said rotor; a yoke carrying the relatively stationary part of said thrust bearing; adjustable means for connecting said casing with said yoke, said adjustable means comprising at least one eccentric rotatably mounted on said yoke, a lever secured to said at least one eccentric, and adjustable means for holding the movable end of said lever.

2. In an elastic fluid turbine, the combination comprising: a casing; a rotor within said casing; a thrust bearing for said rotor; supporting means for carrying the relatively stationary part of said thrust bearing; and adjustable means for connecting said casing with said supporting means, said adjustable means comprising at least one eccentric rotatably mounted on said supporting means, at least one member carried by said casing and pivotally engaging said eccentric, and means for rotating said eccentric.

3. In an elastic fluid turbine, the combination comprising: a casing; a rotor within said casing; a thrust bearing for said rotor; supporting means for carrying the relatively stationary part of said thrust bearing; and adjustable means for connecting said casing with said supporting means, said adjustable means comprising at least one eccentric rotatably mounted on said supporting means, at least one link pivotally connected to said casing and pivotally engaging said eccentric, and means for rotating said eccentric.

4. In an elastic fluid turbine, the combination comprising: a casing, a rotor within said casing; a thrust bearing for said rotor; a yoke carrying the relatively stationary part of said thrust bearing;

ing; adjustable means for connecting said casing with said yoke, said adjustable means comprising eccentric rotatably mounted on said yoke, members carried by said casing and engaging said eccentric, levers secured to said eccentric, and adjustable means for holding the movable ends of said levers.

5. In an elastic fluid turbine, the combination comprising: a casing; a rotor within said casing; a thrust bearing for said rotor; a yoke carrying the relatively stationary part of said thrust bearing; adjustable means for connecting said casing with said yoke, said adjustable means comprising eccentric rotatably mounted on said yoke, links pivotally connected to said casing and engaging said eccentric, levers secured to said eccentric, and adjustable means for holding the movable ends of said levers.

6. In an elastic fluid turbine, the combination comprising: a casing; a rotor within said casing; a thrust bearing for said rotor; a yoke carrying the relatively stationary part of said thrust bearing; and adjustable means for connecting said casing with said yoke, said adjustable means comprising eccentric rotatably mounted on said yoke, members carried by said casing and engaging said eccentric, levers secured to said eccentric, adjustable means for holding the movable ends of said levers comprising a threaded rod held against longitudinal movement, a block having a threaded opening cooperating with said threaded rod, and means for slidably connecting said levers to said block.

7. In an elastic fluid turbine, the combination comprising: a casing; a rotor within said casing; a thrust bearing for said rotor; a yoke carrying the relatively stationary part of said thrust bearing; and adjustable means for connecting said casing with said yoke, said adjustable means comprising eccentric rotatably mounted on said yoke, links pivotally connected to said casing and engaging said eccentric, levers secured to said eccentric, adjustable means for holding the movable ends of said levers comprising a threaded rod held against longitudinal movement, a block having a threaded opening cooperating with said threaded rod, and means for slidably connecting said levers to said block.

8. In an elastic fluid turbine, the combination comprising: a casing; a rotor within said casing; a thrust bearing for said rotor; a yoke carrying the relatively stationary part of said thrust bearing; adjustable means for connecting said casing with said yoke, said adjustable means comprising eccentric rotatably mounted on said yoke, links pivotally connected to said casing and engaging

said eccentric, levers secured to said eccentric, and adjustable means for holding the movable free ends of said levers; and means for limiting the displacement of said yoke relative to said casing, said means comprising flanges on said links adapted to abut bearing surfaces on said yoke when displacement of said yoke relative to said casing is a predetermined maximum or minimum.

10. 9. In an elastic fluid turbine, the combination comprising: a casing; a rotor within said casing; a thrust bearing for said rotor; supporting means for carrying the relatively stationary part of said thrust bearing, said supporting means being separate from said casing; and longitudinally adjustable means for connecting said casing with said supporting means, said adjustable means comprising at least one link connected at one end to said casing to pivot about a given axis; and an eccentric rotatably mounted on said supporting means and pivotally engaging the other end of said link, the axis of said eccentric being substantially parallel to said given axis to permit free lateral expansion and contraction of said casing.

15. 10. In an elastic fluid turbine, the combination comprising: a turbine casing; a thrust bearing; a rotor extending through said casing and guided in said thrust bearing; a bearing casing carrying said thrust bearing, said bearing casing being separate from said turbine casing; and means adjustable longitudinally of said rotor and interposed between said casings for maintaining a preselected clearance between said rotor and said turbine casing, said adjustable means comprising a member, a first connecting means joining said member to said turbine casing and a second connecting means joining said member to said bearing casing, at least one of said connecting means comprising a pivotal structure having rotatable relatively eccentric portions engaging said member and one of said casings respectively and jointly rotatable to cause relative longitudinal movement of said casings.
